United States Patent Office

Des. 192,444
Patented Mar. 20, 1962

192,444

AIRCRAFT INSTRUMENT

Stephen A. McClellan, Earlysville, Va., and Ivan O. Fieldgate, Halesite, N.Y., assignors to Specialties, Incorporated, Syosset, N.Y., a corporation of New York

Filed Feb. 15, 1960, Ser. No. 59,413

Term of patent 14 years

(Cl. D52—6)

FIGURE 1 is a front elevational view of an aircraft instrument, showing our new design.

FIGURE 2 is a side view thereof.

FIGURE 3 is a rear elevation thereof with the portions shown in full lines in FIGURES 1, 2 and 4 omitted for convenience of illustration; and

FIGURE 4 is a cross-sectional view on the line 4—4 of FIGURE 1.

The essential features of the design reside in the portions shown in full lines.

We claim:

The ornamental design for an aircraft instrument, as shown and described.
